UNITED STATES PATENT OFFICE.

WILLIAM LEUCKERT, OF NEW YORK, N. Y., ASSIGNOR OF ONE-HALF TO CHARLES S. HOFFMAN, OF NEW YORK, N. Y.

LIGHT-REGULATOR FOR AUTOMOBILES.

961,621.

Specification of Letters Patent. Patented June 14, 1910.

Application filed May 6, 1909. Serial No. 494,466.

To all whom it may concern:

Be it known that I, WILLIAM LEUCKERT, a citizen of the United States of America, residing in New York, in the borough of 5 Manhattan, county and State of New York, have invented certain new and useful Improvements in Light-Regulators for Automobiles, of which the following is a specification.

10 This invention relates to an improved light-regulator for automobiles.

The larger sizes of automobiles are provided with five lamps, namely, two headlights, two side-lights and a tail-light. In 15 the city of New York, and perhaps in other large cities, the use of the glaring headlights is prohibited within the city limits, so that only the side and tail lights can be used. Outside of the city limits the headlights are 20 usually switched in. The preferred fuel is acetylene-gas, which is carried along, under pressure, in a tank supported on the frame of the automobile.

The object of this invention is to furnish 25 a regulator for the headlights, and eventually for the side and tail lights, by which the lights are fully controlled for full light, a small flame, or shut off entirely when returning to the garage; and for this purpose 30 the invention consists of a light-regulator for automobiles which comprises in its general features a three-way cock that is capable of being set to three positions, namely, closed, half open and entirely open, said 35 three-way cock being connected with a gas-supply pipe and two outlet-pipes, which in connection with the ports of the three-way cock permit either a small supply or a full supply of gas to be conducted to the headlights 40 or side and tail lights of the automobile.

The invention relates more in detail to the construction of the three-way cock and its connections, which will be fully described 45 hereinafter and finally pointed out in the claims.

In the accompanying drawings, Figure 1 represents a side-elevation of my improved light-regulator for automobiles, Fig. 2 is a 50 side-elevation, partly in vertical section through the three-way cock, Figs. 3, 4 and 5 are horizontal sections on line 3, 3, Fig. 2, showing the different positions in which the three-way cock can be placed so as to shut 55 off the gas entirely or conduct either a par-

tial or a full supply of gas to the lamps, and Fig. 6 is a top-view of the light-regulator, drawn on a smaller scale, and showing the different positions of the handle when closed or set for a partial or full supply of gas 60 respectively.

Similar letters of reference indicate corresponding parts throughout the several figures.

Referring to the drawings, *a* represents 65 the spigot of a three-way cock which is provided with a handle *a*¹. The spigot *a* is tapered and seated in a correspondingly-shaped bushing *b*, the spigot being tightly fitted into the bushing. The lower threaded 70 end of the spigot *a* is connected by means of a screw-socket *a*², having a nipple *a*³, with a cap *b*¹ screwed on the lower end of the bushing *b*, said cap being connected by a gas-supply pipe *d* with a tank containing acetylene-gas under pressure. The bushing *b* is connected at different heights with two outlet-pipes *d*¹, *d*², which are provided with stopcocks *d*³, *d*⁴ by the adjustment of which the proper pressure under which the gas is to 80 be delivered to the headlights and the side and tail lights of the automobile is regulated. The two outlet-pipes are united into one delivery-pipe *d*⁵, which leads to the headlights of the automobile, being divided 85 into two branches at the proper point, one for each headlight. When it is desired to control also the supply of gas to the side and tail lights, a second regulator, of the same construction, is used, only that in this 90 case the delivery-pipe *d*⁵ is branched out into three branch-pipes, one for each lamp.

The three-way cock and its bushing are enclosed by a sheet-metal casing *e*, which is attached by flanges *e*¹ and screws *e*² to the 95 dashboard of the automobile, in front of the chauffeur, so that the handle or handles *a*¹ of the three-way cock or cocks are within easy reach. When two regulators are used, they are arranged side by side. The casing 100 *e* serves for protecting the regulating device and the outlet-pipes, and bears on its top-plate *e*³ the indicating marks for the closed, half-open and open positions of the three-way cock, as shown in Fig. 6. To the spigot 105 is attached an indicator *i*, which is moved with the handle *a*¹ over the top-plate into the position required.

The spigot *a* is provided with several ports. A large port *o* registers with an 110

opening o^1 in the bushing with which the outlet-pipe d^2 for the full supply of gas is connected, as shown in Fig. 5. The spigot a is further provided, at a point diametrically opposite to the opening o' , but somewhat above the larger port o , with a smaller port o^2 which registers with a small opening o^3 of corresponding size in the bushing b , said opening o^3 being connected with the outlet-pipe d^1 for the smaller or partial supply of gas, as shown in Fig. 4. From the smaller opening o^2 extends a quadrantal channel o^4 on the outer circumference of the spigot, which connects, when a full supply of gas is to be delivered, the interior of the spigot a by the ports o , o^1 and o^2 , o^3 with both outlet-pipes d^1 , d^2 , as shown in Fig. 5, so that a full supply is delivered by the outlet-pipe d^2 and a small supply by the outlet-pipe d^1 to the burners of the headlights.

Fig. 3 shows the position of the three-way cock when the gas is shut off. In this position neither one of the outlet-ports of the spigot is connected with the outlet-openings of the bushing. The three-way cock is placed into this position when the automobile is returned to the garage. When the automobile leaves the garage, or when the lights are to be lighted on the approach of night, the three-way cock is set from the position shown in Fig. 3, into the position shown in Fig. 4, by turning the handle a^1 for an angle of 90° into the half-open position of the stop-cock. This brings the port o^2 into register with the outlet-opening o^3 of the bushing, so that a small supply of gas is conducted through the outlet-pipe d^1 to the headlights so as to permit the lighting of the burners of the same and keep them burning with a small flame. When it is then desired to give the headlights a full supply of gas, the handle is again turned for an angle of 90° so as to bring the spigot into entirely-open position, in which case the port o of the spigot is placed into register with the opening o^1 of the bushing and instantly a full supply of gas turned on the headlights. In this case not only the full supply passing through the delivery-pipe d^2 , but also the small supply of gas that is conducted through the opening o^2 , the quadrantal channel o^4 and outlet-opening o^3 is conducted to the delivery-pipe d^1 , so that the quick changing of the headlights to full flame, or by returning the handle to half-open position the quick return of the headlights from full flame to small flame, is obtained, without any fluctuation, which would not be the case if the quadrantal connecting channel were not employed, as by the use of the same the quick enlargement or reduction of the flames of the headlights is produced. This position of the spigot is shown in Fig. 5.

By arranging the cap b^1 at the lower end of the bushing, a sufficient space is provided

from which the gas is supplied to the short nipple a^3 of the spigot, while at the same time the air-tight connection between the supply-pipe d and the bushing of the spigot is obtained, so that a steady supply of gas to the spigot of the three-way cock and from the same to the outlet-pipes d^1 , d^2 is secured.

By the arrangement of one light-regulator for the headlights, the headlights are fully within regulating control of the chauffeur. They can be reduced to a small flame when within the city limits and turned on to a large flame when outside of the city, or shut off entirely when returning to the garage.

For regulating also the side and tail lights, a second regulator, side by side with the regulator for the headlights, is arranged, and thereby these lights placed under the same convenient control as the headlights; but the second regulator may be dispensed with as the control of the side and tail lights is not so necessary as the regulation of the headlights, in view of the municipal requirements referred to. It is preferable, however, to have also a regulator for the side and tail lights, owing to the great convenience which the same offers in manipulating the lights from the seat of the chauffeur, while the automobile is in motion, without stopping for lighting them and turning them on for full flame one after the other.

Having thus described my invention, I claim as new and desire to secure by Letters Patent:

1. In a light-regulator, the combination of a bushing having a pair of outlet-openings, and a spigot rotatable in said bushing and having a central opening and having a larger and a smaller opening connected with the central opening for conducting gas, said spigot being provided with an additional channel communicating with said smaller opening and adapted to register with one of the outlet openings of said pair when the larger opening registers with the other outlet opening of said pair.

2. In a light-regulator, the combination of a bushing having an upper and a lower outlet opening, a spigot in said bushing and having a smaller opening adapted to register with the upper outlet opening and a larger opening adapted to register with the lower outlet opening and having a central opening communicating with the larger and smaller openings, and a gas-conducting passage connecting with said central opening, said spigot being provided with a quadrantal channel adapted to register with the upper outlet opening when said larger opening registers with the lower outlet opening.

3. A light-regulator for automobiles comprising a three-way cock consisting of a spigot provided with a handle and indicator, said spigot being provided with ports for a partial or full supply of gas, and a quad-

rantal channel extending on the outer surface of the spigot from the smaller port, a bushing for the spigot provided with a smaller and a larger outlet-opening, outlet-pipes, one connected with the smaller outlet-opening and the other with the larger outlet-opening of the bushing, and a delivery-pipe uniting the outlet-pipes.

In testimony, that I claim the foregoing as my invention, I have signed my name in presence of two subscribing witnesses.

WILLIAM LEUCKERT.
